UNITED STATES PATENT OFFICE.

CHARLES G. NELSON, OF CHICAGO HEIGHTS, ILLINOIS, ASSIGNOR TO ZOURI DRAWN METALS COMPANY, OF CHICAGO HEIGHTS, ILLINOIS, A CORPORATION OF ILLINOIS.

METAL WINDOW SASH.

Application filed February 11, 1926. Serial No. 87,705.

My invention relates to a metal window sash, and particularly to sheet metal clamping members.

The object of my invention is to provide sheet metal clamping members which may be quickly and accurately assembled in clamping position and which are very simple in construction.

The construction and minor objects of my invention will appear as the description proceeds.

In the accompanying drawing forming a part of this specification, Fig. 1 is a transverse section through one form of sash embodying my invention; Fig. 2 is a detail section on the line 2—2 of Fig. 1, and Fig. 3 is a detail showing a different form of face plate from that shown in Fig. 1.

In the construction shown, there is a supporting member 10 beyond one edge of the pane of glass 11 and substantially perpendicular to the plane thereof. Back of the glass, there is a riser 12 rigidly attached to member 10.

A rear clamping member 13 is provided, and is shown attached to the front face of riser 12 by means of a nail or tack 14. Member 13 has a portion 15 at its edge extending towards the glass and a flange 16 adapted to rest against the surface of the glass. Member 13 has a portion 17 resting against support 10, and has an offset portion 18 at the angle between members 10 and 12. Openings 19 are provided at intervals through offset portion 18 where it joins the body of the member.

A front clamping member or face plate 20 is provided with one edge bent to extend towards the glass at 21 and to form a flange 22 resting against the glass. The other edge of member 20 is folded back against itself on the side towards the pane to provide a bead 23 adapted to rest against support 10. The folded portion is reversely bent until it forms a flange 24 extending from the upper edge of bead 23 towards the plane of the pane. Portion 17 of the rear clamping member extends between flange 24 and support 10 and against bead 23. Preferably, tongues 25 are slit at intervals in the edge of portion 17, and are bent to rest against the side of flange 24 away from support 10, so that the relation of the edges of rear member 13 and front member 20 is determined by the

interlocking of flange 24 between tongues 25 and the edge of portion 17 and by the abutment of bead 23 against the edge of portion 17.

Holes 26 are provided at intervals through front member 20 in such relation to holes 19 that a screw 27 may pass through each pair of aligning holes and into member 12. Tightening screw 27 results in clamping the glass between flanges 16 and 22 and holding it yielding yet accurately in place. As member 20 is drawn towards the glass by screw 27, it rocks on bead 23, which in turn presses against the front edge of portion 17. Flange 24 may be spaced slightly above portion 17, as shown, so that it will not interfere with the above described rocking movement, while tongues 25 hold flange 24 in place so that bead 23 cannot slip over the edge of portion 17.

Holes 19 and 26 furnish guides for screws 27, so that the angle of the screws is predetermined and uniform, which aids in holding the clamping member in place uniformly throughout its length and in a predetermined manner to best perform its function. The off-setting of portion 19 increases this guiding effect, and it also makes provision for portion 17 to yield slightly when pressed by bead 23.

If desired, bead 23 might be omitted and the engagement between flange 24, portion 17 and tongues 25 might be depended upon to retain the inner and outer member in proper relative positions, but I prefer to use bead 23, as it conceals the edge of portion 17 in addition to furnishing a reliable anchorage for the edge of member 20.

In Fig. 3 a modified form of outer clamping member or face plate 20^a is shown in section, the parts corresponding to those shown in Fig. 1 being designated by the same reference characters with the letter "a" added. It will be noted that, while the shape of the face plate is considerably modified, it co-operates with other portions 100 of the device in the same way as the face plate shown in Fig. 1.

In Fig. 3 the flange 24^a is shown in contact with the subjacent portion of member 17^a, and the tongue 25^a is not bent up as much as tongue 25 in Fig. 1. It will be understood that the exact elevation of flange 24 or 24^a or the angle of tongue 25

or 25^a is a matter of detail which may be varied within considerable limits and still operate successfully.

Various changes may be made in the inner clamping member and in the means for holding the outer clamping member in place, while retaining some of the advantages of the structure of the outer member, and various changes, besides those described, may be made in the outer member and in the manner of holding it in place while retaining some of the advantages of the structure of the inner member. Obvious changes, other than those mentioned above, may be made within the scope of the appended claims which define the invention.

What I claim is:

1. In a support for a window pane, a supporting member beyond one edge of the pane and approximately perpendicular to the plane of the pane, and a clamping member having one edge adapted to rest against the pane, having a bead along its other edge adapted to rest against said supporting member and constitute a rocking support for the clamping member and having a flange adjacent the bead adapted to extend towards the plane of the pane and spaced away from said supporting member.
2. In a support for a window pane, a supporting member beyond one edge of the pane and approximately perpendicular to the plane of the pane, a clamping member having one edge adapted to rest against the pane, having a bead along its other edge adapted to rest against said supporting member and having a flange adjacent the bead adapted to extend towards the plane of the pane and spaced away from said supporting member and means adapted to contact said flange and resist its movement away from said support.
3. In a support for a window pane, a supporting member beyond one edge of the pane and approximately perpendicular to the plane of the pane, a clamping member having one edge adapted to rest against the pane, having a bead along its other edge adapted to rest against said supporting member and having a flange adjacent the bead adapted to extend towards the plane of the pane and spaced away from said supporting member, means adapted to abut against and resist the inward movement of the bead and means to resist the movement of the flange away from said support.
4. In a support for a window pane, a supporting member beyond one edge of the pane and approximately perpendicular to the plane of the pane, a clamping member having one edge adapted to rest against the pane, having a bead along its other edge adapted to rest against said supporting member and having a flange adjacent the bead adapted to extend towards the plane

of the pane and spaced away from said supporting member, means to draw the clamping member towards the plane of the pane, means to resist the movement of the bead towards the plane of the pane, thus constituting an abutment about which the clamping member may rock, and means to resist the movement of the flange away from said support.

5. In a metal window sash, inner and outer clamping members, each having one edge adapted to rest against a pane of glass and having the other edge provided with a flange beyond the edge of the pane and approximately perpendicular to the plane of the pane, said flanges being adapted to overlap each other and the overlapping portion of one of the flanges having tongues struck therefrom and engaging the opposite face of the other flange.

6. In a support for a window pane, a supporting member beyond one edge of the pane and approximately perpendicular to the plane of the pane, a clamping member having one edge adapted to rest against the pane, having a bead along its other edge adapted to rest against said supporting member and having a flange adjacent the bead adapted to extend towards the plane of the pane and spaced away from said supporting member and another clamping member having one edge adapted to rest against the side of the pane opposite the first said clamping member and having a flange on its other edge adapted to extend between the first said flange and said support.

7. In a support for a window pane, a supporting member beyond one edge of the pane and approximately perpendicular to the plane of the pane, a clamping member having one edge adapted to rest against the pane, having a bead along its other edge adapted to rest against said supporting member and having a flange adjacent the bead adapted to extend towards the plane of the pane and spaced away from said supporting member and another clamping member having one edge adapted to rest against the side of the pane opposite the first said clamping member and having a flange on its other edge adapted to extend between the first said flange and said support, there being tongues on the edge of the second said flange adapted to rest against the side of the first said flange away from said support.

8. In a window pane support, a supporting member having a surface substantially parallel with the plane of the pane and extending beyond the edge of the pane, an inner clamping member between the support and the pane, having one edge adapted to rest against the pane and a flange along its other edge beyond the edge of the pane and extending across the plane of the pane, an

- outer clamping member having one edge adapted to rest against the pane and a flange along its other edge beyond the edge of the pane and extending across the plane of the pane, an 40 outer clamping member having one edge adapted to rest against the pane with the other edge resting against the edge of said flange and overlapping the inner face thereof, said inner clamping member also having integral portions extending between the glass and the overlapping portion of the outer clamping member and engaging the latter, and means to draw the outer clamping member towards said support.
9. In a window pane support, a supporting member having a surface substantially parallel with the plane of the pane and extending beyond the edge of the pane, an 15 inner clamping member between the support and the pane, having one edge adapted to rest against the pane and a flange along its other edge beyond the edge of the pane and extending across the plane of the pane, an 20 outer clamping member having one edge adapted to rest against the pane with the other edge resting against the edge of said flange and overlapping the inner face thereof, said inner clamping member also having integral portions extending between the glass and the overlapping portion of the outer clamping member and engaging the latter, the inner clamping member having an offset portion where the flange joins the body 50 thereof, there being aligning holes through the outer member and the offset portion of the inner member, and screws passing through said holes into the face of said support which is parallel to the plane of the 55 glass.
10. In a window pane support, an inner sheet-metal clamping member having a flange adapted to rest against the pane, a body portion adapted to rest against a supporting surface parallel with the pane and a flange extending across the plane of the pane beyond one edge of the pane, there being an offset portion where the last said flange joins the body and portions of the 60 edge of the second said flange being bent from the plane of the flange in the form of tongues to receive the edge of a second clamping member between said tongues and the adjacent portion of the body from 65 which the tongues are struck.
11. In a window pane support, an inner sheet-metal clamping member having a flange adapted to rest against the pane, a body portion adapted to rest against a supporting surface parallel with the pane and a flange extending across the plane of the pane beyond one edge of the pane, there being an offset portion where the last said flange joins the body and portions of the 70 edge of the second said flange being bent from the plane of the flange in the form of tongues to receive the edge of a second clamping member between said tongues and the adjacent portion of the body from 75 which the tongues are struck.
- In testimony whereof I have hereunto signed my name to this specification.

CHARLES G. NELSON.
